Lee W. Barker, 443 Alhambra Road, South San
Francisco, Calif. 94080

Filed July 13, 1966, Ser. No. 3,065

Term of patent 14 years

(Cl. D95—5)

FIG. 1.

FIG. 2.

FIG. 3.

FIG. 1 is a side elevational view of sheet metal snips showing my new design with the jaws thereof partially opened;

FIG. 2 is a plan view thereof, as observed from the top of FIG. 1, with the jaws closed;

FIG. 3 is an elevational view taken from the opposite side from that of FIG. 1;

FIG. 4 is a side elevational view of another embodiment of the sheet metal snips shown in FIG. 1 wherein the exterior handle portions thereof are provided with an oval recess and the latching means at the jaws has been omitted therefrom;

FIG. 5 is a plan view thereof, as observed from the top of FIG. 4, with the jaws closed; and

FIG. 6 is an elevational view taken from the opposite side from that of FIG. 4.

I claim:

The ornamental design for sheet metal snips, substantially as shown and described.
